CARTON

Kenneth B. Jones, San Francisco, Calif., assignor to Barrett & Hilp, San Francisco, Calif., a copartnership composed of J. Frank Barrett and Harry H. Hilp

Application October 3, 1938, Serial No. 232,914

2 Claims. (Cl. 229—37)

This invention relates generally to packaging cartons of the type commonly made from fibreboard stock, and which are used for the purpose of shipping and storing various articles, such as 5 canned or bottled goods.

It is an object of the invention to provide a carton of the above character which will serve all of the normal purposes of a packaging and shipping container, but which will have provision 10 for forming a convenient carrying grip for use by the consumer either before or while the articles are being removed from the carton.

Further objects of the invention will appear from the following description in which the preferred embodiment of the invention has been set forth in detail in conjunction with the accompanying drawing.

Referring to the drawing:

Fig. 1 is a perspective view illustrating a carton incorporating the present invention.

Fig. 2 is a perspective view of the same carton shown in Fig. 1, with certain flaps being bent back from closed position to form a carrying grip.

Fig. 3 is a transverse cross-sectional detail through the carton as illustrated in Fig. 1.

Fig. 4 is a transverse cross-sectional detail taken through the carton as it appears in Fig. 2.

Fig. 5 is a fragmentary elevational view showing a modified construction.

Fig. 6 is a cross sectional view taken on the line 6—6 of Fig. 5.

The carton comprising the present invention is made of suitable fibreboard stock, which may 35 be either corrugated or solid. In accordance with conventional designs, a single sheet of the fibreboard stock can be cut to suitable shape and scarfed to form lines of bend, whereby a simple rectangularly contoured container can be as-

sembled as illustrated in Fig. 1. Briefly the assembled carton as illustrated includes the side and end walls 10 and 11, together with what normally constitutes the top and bottom walls 12 and 13. These top and bottom walls are 40 formed of the several flaps 14, 15 and 16, which are attached to the edges of the side and end walls 10 and 11. In a typical assembly flaps 14 and 15 are folded down upon top of the flaps 16, and are secured thereto by the use of a suitable glue or adhesive.

In carrying out the present invention the two flaps 15 are provided with openings 17, and when these flaps are swung back to bring their free 55 edges into contact as illustrated in Fig. 2, the openings 17 are brought into registry to form a convenient carrying grip. In connection with Fig. 2 it should be noted that after stripping flaps 15 from the flaps 16, to form the hand grip as 60 illustrated in this figure, the lower longitudinal

flaps 14 may remain attached to flaps 16, thus lending sufficient strength to the carton to avoid sagging under the weight of the contents. Furthermore when the flaps 16 are proportioned substantially as illustrated, a slot or opening is 5 formed between their free edges by means of which one may have partial access to the interior of the carton, for the removal of the articles. If desired at the time the carton is packed with goods, insert sheets 18 may be laid adjacent the 10 inner surface of the flaps 16, thus affording a temporary closure after stripping back the flaps 15, which may be readily removed when desired to permit free access to the interior of the car- 15 ton.

Figs. 5 and 6 illustrate a further embodiment for the purpose of forming a more comfortable type of hand grip. In this instance in forming an opening 17 in one of the flaps 15, a tongue 19 is provided which can be bent to extend through 20 the other opening 17, when the flaps are positioned as illustrated in Fig. 2. By this arrangement a rounded and smooth surface is presented to the fingers, in contrast to sharp edges which may be presented by the edges of the fibreboard 25 with the arrangement of Fig. 4.

It will be evident from the foregoing that my carton accomplishes the result of affording a convenient carrying grip, without in any way materially increasing cost of manufacture, and 30 without adding additional parts or elements to the carton. The longitudinal flaps 15 may be said to perform two functions, one being the usual function of cooperating with the remainder of the flaps to form the closed top and bottom walls of 35 the carton, and the other being to form the convenient carrying grip for the carton, when the carton reaches a consumer.

I claim:

1. In a packaging carton, fibreboard stock 40 forming a rectangularly contoured carton having six walls, the top and bottom walls being formed by fibreboard flaps attached to the side and end walls, two of the flaps attached to a common side wall being provided with openings adapted 45 to be brought in registry to form a carrying grip when said flaps are bent back to a position with their free edges substantially in contact.

2. In a packaging carton, fibreboard stock 50 forming a rectangularly contoured carton formed of six walls, the top and bottom walls being each formed of four flaps which are attached to the side and end walls, two flaps which are attached to a common side wall being of a length sufficient 55 to enable their free edges to be brought substantially in contact when bent back to closed position, said flaps being provided with registering openings to form a carrying grip for the carton.

KENNETH B. JONES.
